Primary Examiner — Holly Baynam

(74) Attorney, Agent, or Firm — Brooks Kushman P.C.

(57) **CLAIM**

The ornamental design for a furniture glide for leg end with replaceable end cap, as shown and described.

DESCRIPTION

FIG. 1 is a perspective view of the furniture glide for leg end with replaceable end cap of the present invention;

FIG. 2 is a bottom plan view thereof;

FIG. 3 is a side elevation view thereof; and,

FIG. 4 is a top plan view thereof, partially shown in phantom lines.

The broken lines are for illustrative purposes only and form no part of the claimed design.

The broken lines showing the interior of the furniture glide are for the purposes of illustrating environment and form no part of the claimed design.
